FIG. 1 is a perspective view of a desk top storage cabinet in accordance with my new design, showing the left side, front and top thereof;

FIG. 2 is a rear elevation of the desk top storage cabinet of FIG. 1;

FIG. 3 is a right side elevation of the desk top storage cabinet of FIG. 1; and

FIG. 4 is a front elevation of the desk top storage cabinet of FIG. 1.

The desk top storage cabinet of my invention may have variable lateral dimensions, and the desk top storage cabinet is shown broken away at the center in FIGS. 1, 2 and 4 to indicate indeterminate length.

The design is characterized by the multiple shelf arrangement in combination with a pair of door elements as best illustrated in FIG. 1.

I claim:

The ornamental design for the desk top storage cabinet, as shown and described.
